SUCTION NOZZLE

Axel Albert Forsberg, Essingen, Stockholm, Sweden, assignor to Electrolux Corporation, Dover, Del., a corporation of Delaware

Application November 18, 1938, Serial No. 241,217
In Germany November 19, 1937

3 Claims. (Cl. 15—155)

My invention relates to vacuum cleaners and more particularly to an improved suction nozzle.

In accordance with the present invention a nozzle is provided having an elongated suction opening adapted for use in removing ordinary dust and dirt from a rug, or other surfaces to be cleaned, and which is provided with a pivoted member which may be swung into a position for reducing the effective cross-sectional area of the nozzle opening. This serves to concentrate the air flow at a comparatively small area, thus making the nozzle effective for removing threads, dog or cat hairs, or other smaller objects which adhere tenaciously to the surfaces being cleaned.

In order to reduce the effective cross-sectional area of the nozzle the pivotal member is arranged to be swung into such a position that it blocks off a considerable proportion of the area of the nozzle opening. When in this position the effect of the suction is to retain it, thus reducing the ease with which it may be returned to its original position when it is desired to make use of the full cross-section of the nozzle opening.

In accordance with the present invention, means are provided whereby the strong suction which tends to hold the pivoted member in a position reducing the cross-sectional area of the nozzle opening, is broken by merely lifting the nozzle from the surfaces being cleaned, thereby permitting the member to be returned to its inoperative position.

Further objects and advantages of my invention will be apparent from the following description, considered in connection with the accompanying drawings which form part of this specification and of which:

Fig. 1 is a bottom view of a nozzle in accordance with the present invention;

Fig. 2 is a cross-sectional view taken on the line 2—2 of Fig. 1;

Fig. 3 is a view similar to Fig. 1, but with certain parts in a different position;

Fig. 4 is a cross-sectional view taken on the line 4—4 of Fig. 3;

Fig. 5 is a bottom view of a portion of a nozzle in accordance with a second embodiment of my invention;

Fig. 6 is a cross-sectional view taken on the line 6—6 of Fig. 5; and

Fig. 7 is a cross-sectional view taken on the line 7—7 of Fig. 5.

Referring more particularly to Figs. 1 through 4, reference character 10 designates a nozzle body which is formed with an elongated suction opening 11. This opening is bounded in part by for-

ward lips 12 and 13 and rear lips 14 and 15, the ends of lips 12 and 14 and lips 13 and 15 being joined together at the ends of the nozzle.

Rotatably secured to the nozzle body 10 is a hollow cylindrical member 16 formed with an opening 17 which establishes communication between the interior of the body 10 and the interior of the member 16. Secured to the member 16 and communicating therewith is a connecting member 18, the opposite end of which is adapted to receive a conduit leading to a source of suction.

When the nozzle is placed with the lips on a surface to be cleaned, the space between the forward lips 12 and 13 provides a narrow slot 19. Between the lips 12 and 14 and between the lips 13 and 15 the depth of the interior of the nozzle body is indicated by the distance *a*, while opposite the slot 19, the depth of the interior of the nozzle body is limited only by the member 16. Between the rear lips 14 and 15 there is pivotally mounted a member 20. This member is formed with a lip 21 which, when the member is in the position shown in Figs. 1 and 2, forms a continuation of the rear lips 14 and 15. Member 20 is formed with a central opening 22 and this opening, on the opposite side of the member from the lip 21, is completely bounded by a lip 23.

The lateral dimension of the member 20 is such that, when it is swung to the position shown in Figs. 3 and 4, a narrow passageway 24 is formed between the edge of member 20 and the inner wall of the nozzle body 10, this passageway communicating with the aforesaid slot 19. Member 20 is slightly longer than the deep central portion of the nozzle and consequently, when the member 20 is in the position shown in Figs. 3 and 4, it blocks off flow to the central portion from the shallow end portions. The extent of lip 23 is such that, when the member 20 is in the position as shown in Figs. 3 and 4, this lip raises the forward lips 12 and 13 of the nozzle slightly away from the surface. Thus, it is assured that the lip 23 is held against the surface being cleaned and tends to prevent the flow of air into the nozzle through the opening 22, thus causing substantially all of the air to flow through the narrow passage 24.

However, when the nozzle is lifted bodily from the surface, air may flow into the nozzle body through the opening 22, and this opening is large enough so that the flow of air therethrough is sufficient to break the suction which would otherwise tend to hold the member 20 within the opening 11. Due to the location of the pivots

upon which the member 20 is mounted, when the nozzle is raised from the floor and the suction broken as aforesaid, the member 20 swings in the direction of the arrow shown in Fig. 4 to a position somewhat beyond the vertical. If the nozzle is then lowered towards the floor before the member 20 has a chance to swing back, the member 20 is caused to take the position shown in Figs. 1 and 2. In order to pivot the member 10 20 from this position to the position shown in Figs. 3 and 4, the nozzle is again raised from the floor, whereupon gravity causes the member to pivot as indicated by the arrow in Fig. 2.

In the embodiment shown in Figs. 5 through 7, 15 similar parts are designated by the same reference characters as in Figs. 1 through 4. This embodiment differs from that above described in that the pivoted member, here designated by reference character 25 does not itself completely 20 form the opening 22, but this opening is in part bounded by a lip 26 which is part of the nozzle body 10. The member is pivoted to opposite ends of the lip 26 by means of pins 27. The downward extension of lip 26 is such that it contacts the surface being cleaned and hence prevents the flow of air through the opening 21 when the nozzle is against such surface. The lip 28, 25 which surrounds that portion of the opening 22 which is bounded by the member 25 also contacts the surface being cleaned when the member 25 is in the position shown, thus causing substantially all of the air to pass through the passage 24.

The operation of this embodiment is similar to that described above in connection with the 30 embodiment shown in Figs. 1 through 4 and hence need not be repeated.

While I have shown two more or less specific 35 embodiments of my invention, it is to be understood that this has been done for purposes of illustrations only and that my invention is not limited thereto but the scope thereof is to be determined by the appended claims.

I claim:

1. In a suction nozzle for cleaning a surface, 40 a hollow body formed with a cleaning opening bounded by lips, and a member movable with relation to said body from a position outside said opening to a position reducing the effective cross-sectional area of said opening, the dimensions 45 of said member being such with respect to those of said opening that when the member is in the second-mentioned position there is provided a small opening between said member and one of said lips, the portion of said lip adjacent to said small opening being cut away to provide a passage for flow of air over said surface and into said small opening, said member having a passage forming an auxiliary air inlet to said hollow

body when said member is in the second-mentioned position and spaced from said surface, the material bounding said auxiliary inlet on the side thereof which is adjacent to said surface when the member is in said second-mentioned position 5 extending downwardly to contact said surface when the nozzle is in operative position on the surface.

2. In a suction nozzle for cleaning a surface, a hollow body formed with a cleaning opening 10 bounded by lips, a member movable with relation to said body from a position outside said opening to a position within the opening, the dimensions of said member being such with respect to those of said opening that when the 15 member is in the second-mentioned position there is provided a small opening between said member and one of said lips, the portion of said lip adjacent to said small opening being cut away to provide a passage for flow of air over said 20 surface and into said small opening, said member having a passage forming an auxiliary air inlet to said hollow body when said member is in the second-mentioned position and spaced from said surface, and a rim on said member 25 around said auxiliary inlet on the side thereof which is adjacent to said surface when the member is in said second-mentioned position, said rim extending downwardly to contact said surface when the nozzle is in operative position on 30 the surface.

3. In a suction nozzle for cleaning a surface, a hollow body formed with a cleaning opening bounded by lips, a member movable with relation to said body from a position outside said opening to a position within the opening, the dimensions of said member being such with respect to those of said opening that when the member is in the second-mentioned position there is provided a small opening between said member and 35 one of said lips, the portion of said lip adjacent to said small opening being cut away to provide a passage for flow of air over said surface and into said small opening, said member together with another of said lips bounding a passage- 40 way which forms an auxiliary air inlet to said hollow body when the member is in the second-mentioned position and spaced from said surface, and a rim on said member around the portion of said auxiliary inlet which is bounded by 45 said member, said rim being on the side of the member which is adjacent to said surface when the member is in said second-mentioned position and extending downwardly to contact said surface when the nozzle is in operative position on 50 the surface.

AXEL ALBERT FORSBERG.
